THERMAL ELECTRIC FUSE

Frank C. La Mar, New York, N. Y., assignor to
 Great Western Fuse Company, New York, N. Y.,
 a corporation of Delaware

Application March 29, 1932, Serial No. 601,732

6 Claims. (Cl. 200—119)

This invention relates to conductors, particularly to protective devices therefor, and more especially to thermal or fusible protective devices.

A principal object of this invention is the production of a cartridge type electric fuse of such construction that the fusible element thereof may be renewed without the use of tools, and at the same time is such that the insertion of an improper fusible element is prevented.

10 Other objects and advantages will appear as the description of the particular physical embodiment selected to illustrate the invention progresses and the novel features will be particularly pointed out in the appended claims.

15 In describing the invention in detail and the particular physical embodiment selected to illustrate the invention, reference will be had to the accompanying drawing and the several views thereon, in which like parts are designated by the 20 same characters throughout the several views, and in which:

Figure 1 is a cross-sectional view of a cartridge type fuse embodying applicant's invention; Fig. 2 is a cross-sectional view of the same device as 25 shown by Fig. 1, but taken on a plane at a right angle to the plane upon which Fig. 1 is taken; Fig. 3 is a cross-sectional view of the device as shown by Fig. 1 on a plane indicated by the line III—III of Fig. 1 viewed in the direction of the 30 arrows at the ends of the line; Fig. 4 is a view corresponding to Fig. 3, but showing the parts in a slightly different relation, to illustrate the adaptability of the device to fusible elements of different thickness; Fig. 5 is a detailed view of an operating 35 lever used in applicant's invention; Fig. 6 is a view of a portion of a device as shown by Fig. 1 illustrating a position of the operating levers preparatory to renewing the fusible element.

Numeral 1 designates the ordinary and well 40 known insulating tubular shell as ordinarily used in cartridge type electric fuses. This shell may be of any desired and appropriate material such as horn fibre. Each end of the shell 1 carries a ferrule 2. In the form shown the ferrule embraces 45 the outer periphery of the shell 1 and is suitably attached thereto so as not to rotate independently thereof by means of the tight fit, and the supplementary rivet 3.

The ferrule 2 has its outer end 4 threaded for 50 the reception of an apertured threaded thimble 6. The aperture 7 of the thimble is such that a shoulder 8 is formed.

A metallic knife blade 9 is positioned in the 55 aperture of the thimble 6. This knife blade has a shoulder 10 rigidly attached thereto.

A washer 11 is provided which is formed with a slot 12 to just fit over and around the knife blade. The washer 11 is positioned against the shoulder 10 and one surface bears against the end 13 of the ferrule, while the opposite surface bears 60 against the flange 8 of the thimble. This construction prevents the knife blade 9 from moving outwardly.

In order to prevent the knife blade from moving inwardly, an insulating bar 14 is rigidly attached to both the knife blade 9 and the opposite knife blade 15 so that neither knife blade can move inwardly, and as the ends of the fuse are built symmetrically and identically neither knife blade, nor oppositely disposed contacting 65 conducting member, can move outwardly.

The thermal or fusible element is in the form, as shown by Fig. 6, designated 16. It has slots 17 and 18 which fit around the stem of bolts 19 and 20 and is held in place by pressure exerted by the 75 heads 21 and 22 of the bolts 19 and 20 respectively, being bound between the heads and the knife blades.

All of the constructions hereinbefore described are old and well known. Heretofore, however, 80 the heads 21 and 22 have been provided with a screw driver slot so that the insertion or removal of a thermal element such as 16 required the use of a screw driver or similar tool. Applicant's invention is designed to obviate the use 85 either of a screw driver or any other tool in the operation of removing or replacing a thermal element.

Applicant provides bolts, such as 19 and 20 which are provided with an enlarged head, as 21, 90 and with a screw thread as 23. The knife blades, as 9, are also provided with an internal screw thread cooperating with a screw thread 23 of the bolt, as 19. The turning of the bolt 19 causes the head 21 to approach toward or recede from 95 the knife blade 9 thus binding the thermal element to the knife blade or providing a space in which the thermal element may be inserted preparatory to binding.

In order to turn the bolt 19, applicant provides 100 a plural faced, toothed or mating member, such as a small pinion 24, on each bolt. This pinion is attached rigidly to the bolt 19, preferably by passing a pin such as 25 through the pinion and the bolt 19.

In order to turn the bolt 19 an operating handle 26 is provided, shown in detail in Fig. 5. This operating handle is provided with a mating aperture or internal toothed pinion 27 of such size that it meshes with the pinion 24. When 110

this operating handle is in place upon the pinion 24, and is drawn either to the right or left, as viewed in Fig. 1, the bolt head 21 will be either drawn toward or caused to recede from the 5 surface of the knife blade 9, and so a thermal element may be bound or released for renewal.

In order to hold the operating handle 26 properly in place in mesh with the pinion 24 applicant provides a member to prevent the operating 10 handle 26 from moving outwardly off the pinion. This preferably takes the form of a screw thread 28 upon the bolt 19 and a nut 29 engaging the screw thread.

Although applicant has illustrated a bolt as 15 the binding means, it is to be understood that this is merely illustrative but is not intended to exclude other well known and suitable constructions whereby a head or binding member is caused to approach or recede from a binding 20 face.

With applicant's type of fuse, if it is necessary to replace a fusible element, such as 16, the operating handles 26 are moved from the position as shown in Fig. 1 to the position as 25 shown in Fig. 6. This movement causes the heads 21 and 22 to separate from the face of the knife blades 9 and 15 so that the old fusible element may be removed and a new fusible element put in position. After the new fusible 30 element has been put into position the operating handles 26 are returned to the position as shown in Fig. 1 thereby binding the thermal element firmly between the heads as 21 and 22 and the faces of the knife blades 9 and 15.

35 A custom amongst the makers of cartridge fuses allow certain differences in the capacity of the fusible element used in the same size cartridge. This difference in capacity is exhibited by a difference in thickness of the fusible 40 element, as 16. A lower capacity element would be thinner than a higher capacity element. Applicant provides for this in the construction of his fuse. The pinion 24 is placed in such position upon the bolt 19 that when the bolt is 45 moved to a position in which the pinion bears against an abutment, as the insulating bar 14, the greatest distance possible for the device to exhibit between the under side of the head 21 and the face of the knife blade 19 is obtained. 50 This allows the higher capacity fusible element to be inserted. Of course, anything thinner may be inserted. It is to be observed that the higher capacity is limited. This is in accordance with desire, because although no harm could come 55 from inserting a lower capacity fusible element, much harm could come from inserting an element of a capacity greater than the particular size cartridge is capable of carrying. For this reason applicant's construction is such that a 60 fuse above a given limit cannot be inserted.

It will be readily understood that to secure 65 different openings between the inside of the head 21 and the face of the knife blade 9 different angular movements of the operating handles 26 are required, and that a very thick fusible element under a head, such as 21, might result in the operating handle 26 being in a position at an angle to the position as shown in Fig. 1 when the head 21 is tightly pressed against the fusible element and the fusible element is tightly pressed against the face of the knife blade 9. Applicant's construction provides for this contingency and is particularly designed to provide therefor. In order to have the operating handles in the position as shown in Fig. 1

when the fusible element is in place and the bolt heads are tightened there against, the nut 29 is removed from the bolt 19, the operating handle 26 removed from engagement with the pinion 24 and then turned about the axis of the bolt to such an extent that it will lie in the desired angular position, and then returned into engagement with the pinion, and the nut 29 replaced to hold the operating handle in position. This removal and replacement of the operating handle 26 may be necessary in order to provide the widest possible space between the head 21 and the face of the knife blade 9 and then another removal and replacement may be necessary in order to suitably adjust the operating handle so that it will lie in the position as shown in Fig. 1 when the thermal element has been tightly bound.

Fig. 3 illustrates by the space 30, the fact that a thick fusible element 16 is in place under the head 21 while in Fig. 4 the space 31 indicates that a thin fusible element 16 is under the head 21.

Although I have particularly described one particular physical embodiment of my invention, and described the construction, principle, and mode of operation thereof, nevertheless, I desire to have it understood that the form selected is merely illustrative but does not exhaust the possible physical embodiments of the idea of means underlying my invention.

What I claim as new and desire to secure by Letters Patent of the United States, is:

1. In a fuse of the type in which there are oppositely disposed contact conducting members and a fusible element extends from one to the other, the combination of a threaded bolt formed with an enlarged head in screw threaded engagement with a knife blade, a plural toothed member fixed upon the bolt, an operating handle engageable in different positions with said plural toothed member for rotating said plural toothed member, means for retaining the plural toothed member in an engaged position an abutment for engagement with the plural toothed member for limiting the longitudinal movement of the bolt whereby the bolt may be rotated by an operation of the handle so as to space the head thereof a predetermined distance from the contact conducting member, and means to connect the other end of the fusible element to the other contacting member.

2. In an electrical fuse of the type in which oppositely disposed contacting conducting members connected by a fusible strip are used, the combination of a headed bolt for binding the fusible member between a contacting conducting member and the underside of the head in screw threaded engagement with a contacting conducting member, means for limiting the longitudinal displacement of the bolt, said means including an operating handle, and means for adjusting said operating handle to different angular positions upon said bolt and means for retaining the operating handle in an adjusted angular position.

3. As a binding means for holding a fusible strip to a knife blade terminal, the combination of a threaded bolt formed with an enlarged head in screw threaded engagement with the knife blade, a plural face member fixedly attached to the bolt, an operating handle with corresponding plural faces for cooperation with the plural face member upon the bolt, means for retaining the operating handle in a fixed cooperative position with relation to the plural face member an abut-

ment for limiting the longitudinal displacement of the bolt, whereby a manipulation of the operating handle produces a space between the head of the bolt and the knife blade of no greater 5 than a predetermined amount and whereby the operating handle may be so positioned upon the plural face member that when the fusible member is bound tightly to the knife blade the operating handle will lie substantially in a desired 10 position.

4. In a fuse, a knife blade formed with a screw threaded aperture, a screw threaded bolt engaging the screw threaded aperture, said bolt formed with an enlarged head, whereby a fusible element 15 may be bound between the head and the knife blade, a plural face member fixedly attached to the bolt, an abutment limiting the longitudinal displacement of the bolt, an operating handle formed with an aperture corresponding in size 20 and shape with the plural face member on the bolt, whereby the operating handle may be placed in different positions angularly about the axis of the bolt so that various degrees of longitudinal movement of the bolt may be secured even if adjacent parts obstruct the rotation of the handle and whereby when the head of the bolt is pressed firmly against the fusible element and the fusible 25 element is pressed firmly against the knife blade

the operating handle may lie in a desired position angularly about the axis of the bolt and means for retaining the operating handle in co-operative relation with the plural face member.

5. In a fuse of the type in which a fusible element is bound to a knife blade by being placed between the head of a bolt screw threaded into the knife blade and the knife blade, the combination of a member fixedly attached to the bolt and an operating handle formed to mate with said member on the bolt in a plurality of positions angularly about the axis of the bolt, means for retaining the operating handle in angularly adjusted position and means to limit the longitudinal movement of the bolt. 80

6. In a fuse of the type in which a fusible element is bound to a knife blade by being placed between the head of a bolt and the knife blade, the combination of a member formed with a screw threaded aperture for cooperation with the thread of the bolt, means for limiting longitudinal movement of the bolt, a plural face member on the bolt, a mating operating handle adapted to be placed on the plural face member in a plurality of positions angularly about the axis of the bolt 90 and means for retaining the operating handle in adjusted position on the plural face member. 95
